(57) **CLAIM**

The ornamental design for a flooring module, as shown and described.

DESCRIPTION

FIG. 1 is a top plan of a flooring module showing the new design;

FIG. 2 is a top, front and right side perspective view thereof;

FIG. 3 is a right side elevation thereof;

FIG. 4 is a left side elevation thereof;

FIG. 5 is an enlarged rear elevation thereof;

FIG. 6 is an enlarged front elevation thereof; and,

FIG. 7 is a top plan view showing the flooring module in a position of use within a portion of a floor.

The broken lines shown in FIG. 7 depict portions of the flooring module that are not claimed and that are included to show the design in a position of use.
